UNITED STATES PATENT OFFICE.

FRANK KUHN AND FRANK E. SHAILOR, OF DETROIT, MICHIGAN, ASSIGNORS TO AMERICAN ELECTRICAL HEATER COMPANY, OF DETROIT, MICHIGAN, A CORPORATION OF MICHIGAN.

ELECTRICAL HEATING UNIT.

1,225,826.

Specification of Letters Patent.

Patented May 15, 1917.

Application filed May 8, 1915. Serial No. 26,792.

To all whom it may concern:

Be it known that we, FRANK KUHN and FRANK E. SHAILOR, both citizens of the United States of America, residing at Detroit, in the county of Wayne and State of Michigan, have invented certain new and useful Improvements in Electrical Heating Units, of which the following is a specification, reference being had therein to the accompanying drawings.

The invention relates to electrical heating units, and has for its object the obtaining of a construction in which the heat may be concentrated at points without danger of burning out the circuit or of short circuiting the same. It is a further object to obtain a unit construction which may be built up to form a heater of any desired size or area. With these objects in view the invention comprises the construction as herein-after set forth.

In the drawings:

Figure 1 is a longitudinal section through a heater of our improved construction, showing the units in elevation;

Fig. 2 is an enlarged section through one of the units; and

Fig. 3 is a perspective view thereof.

A is a support of refractory insulating material, such as porcelain, and which is provided with a conical portion. B is a tapering coil of the resistor wire, which is supported upon the conical portion of the insulator and is held thereby from displacement. The small end of the coil B has a terminal portion C, which passes through an axial aperture D in the insulator A, while the large or base coil of the resistor is supported in a groove E and has a terminal F passing through the insulator. Thus the two ends of the coil are securely anchored to the insulator, while the convolutions of the coil are held from displacement by their conical support. The convolutions are preferably in contact with each other, but on account of the slight difference of potential

between the contacting portions there will be practically no leakage of current thereacross.

With the unit constructed as described various forms of electric heaters may be obtained by merely assembling a sufficient number of the units to produce the required resistance. Each unit forms a center of radiation and also a luminous point which has an attractive appearance. As shown in Fig. 1, the units are assembled by being placed in apertures in a front plate G of any suitable material, not necessarily of an insulating nature. A shoulder H on the insulator bears against the rear face of this plate, and a suitable backing plate I may be placed beneath the insulators to inclose the terminal connections. The terminals of each unit extend laterally from the insulator and may be coupled by clamps J or other suitable means. Thus the assembling of any desired number of units is quickly performed, and when the backing plate I is in position it will hold the units from displacement.

What we claim as our invention is:—

1. An electrical heater, comprising a series of units each comprising an insulator support having a conical and a shouldered portion, and a tapering coil seated upon and anchored to said conical portion, means for connecting a plurality of said units in series, a mounting for said units in spaced relation to one side of said means, and an apertured plate supported upon the shouldered portions of said insulator supports upon the opposite side of said connecting means.

2. An electrical heating unit, comprising an insulator support having a conical portion, and a tapering resistor coil engaging said conical portion, having contacting adjacent convolutions of slight resistance.

3. An electrical heating unit, comprising an insulator support having a conical portion, and a tapering close-coiled resistor of slight resistance between convolutions sup-

ported on said conical portion and anchored thereto by a central terminal wire.

4. An electrical heating unit, comprising a tapering insulator support having a conical portion and a central aperture, a resistor coil seated upon the conical portion of said insulator, having contacting adjacent convolutions with but slight difference of potential therebetween, and a terminal extending from the small end of said coil, through

said central aperture, and forming an anchor for retaining said coil.

In testimony whereof we affix our signatures in presence of two witnesses.

FRANK KURN.
FRANK E. SHAILOR.
